UNITED STATES PATENT OFFICE.

THOMAS F. FITZSIMONS, OF BROOKLYN, NEW YORK.

STEAM-POWER PLANT.

Application filed February 23, 1922. Serial No. 538,483.

This invention relates to steam power plants and particularly to the construction and arrangement of the heat exchanging units, including boilers and auxiliary thermal economizing equipment such as feed-water heaters and super-heaters which compose the steam power plants for engines such as locomotives.

In locomotives as heretofore constructed, it has been the practice to make the steam boiler an integral part of the locomotive, the main frame and much of the auxiliary mechanism being securely fixed to the boiler as by riveting. Thus, when any trouble, even the blowing of a single tube, occurred in the boiler, it was necessary to lay up the entire locomotive during the time required to make the necessary repairs. Since most of the defects in locomotives occur in the boiler, many hours were spent in the shop which need not have been if it were possible to quickly replace the defective boiler with one in operative condition.

It is therefore the principal object of this invention to provide a locomotive having a shell containing a boiler which may be readily removed from the shell and easily replaced, these operations requiring but a short time and small expense. Thus, by aid of this invention, a locomotive having boiler trouble is run into the shop, the boiler exchanged and back on the road in a much briefer interval than was heretofore possible.

Superheaters have hitherto been employed to some extent with locomotives, but they have been very expensive to install, and relatively difficult to remove for the repairs which were constantly needed. Another object of this invention is to provide a simple, easily removable superheater to cooperate with the boiler, and to provide means for protecting the superheater from unduly high temperatures, thereby lessening the likelihood of burning out or other defects which would cause maintenance expense.

It is an object of this invention to provide a feed-water heater which is amply supplied with heat, is mounted for ready removal from its operative position and speedy replacement by a clean heater, and is also designed to permit removal of the superheater without displacement of the feed-water heater or the boiler. Further objects will

in part be pointed out and in part be apparent as the description progresses.

Briefly stated, the invention contemplates the provision of a steam power plant comprising a number of heat-exchanging units which are of novel construction themselves to permit greater economy of operation, are independently removable from their normal or operating position, and are easily replaceable.

One embodiment of the invention is illustrated in the accompanying drawings in which:

Fig. 1 is a side elevation of a locomotive embodying the new power plant; 70

Fig. 2 is an enlarged side elevation of a portion of the structure indicated in Fig. 1, but removed from the outer shell;

Fig. 3 is a central longitudinal section of the heat-exchanging units; 75

Fig. 4 is a similar section on an enlarged scale of a novel superheater;

Fig. 5 is a section taken on the line 5—5 of Fig. 3, showing the front of a feed-water heater, and 80

Fig. 6 is a section taken on the line 6—6 of Fig. 3, showing the front of a boiler and superheater.

Referring now particularly to Figs. 1 and 2, there is shown a locomotive having wheels arranged as in the usual Pacific type, the front truck, driving and trailer wheels indicated in dotted lines all being secured by suitable journal boxes and springs, not shown, to the main frame 1 which extends throughout the entire length of the locomotive and carries, by means of suitably secured buckle-plates 2 and arcuate braces 3, the shell 4 which comprises the principal rigid supporting, housing and heat insulating element for the steam generating or heat-exchanging units. 85

A support 5, carried by the main frame, bears against foundation ring 19 and thus supports a firebox or primary combustion chamber 8. The shell 4 extends from the front of the locomotive rearwardly to the back end of the firebox, and preferably comprises forward and waist cylindrical sections 20 and 21 connected by a tapering section 22, together with a crown section 9. Each of these sections has its inner surface covered with a permanently attached lagging of heat insulating material (not shown). These sections are shaped to house 95

a feed-water heater 6, boiler 7 and firebox 8. The waist section 21 of the shell is cylindrical from its front edge rearwardly to the throat of the boiler from which point 5 the lower half is cut away to accommodate the firebox, thus leaving the side sheets 56 with their stay-bolts exposed for easy inspection. The crown of section 21 is cut away to accommodate the removable crown 10 section 9 of the shell, which comprises a dome casing 23 to house a steam dome 24. A cab 10 is detachably secured in any desired manner to the rear edges of shell sections 9 and 21.

15 Boiler 7 surrounds firebox 8 in the usual manner, and extends forward about half-way to the smokebox, and is thus exposed to the gases of combustion at their highest temperature. Forward of the boiler is situated 20 the feed-water heater 6, a space 14 therebetween being enclosed by a frusto-conical wall 25 of suitable material such as cast-iron.

25 As seen in Figs. 5 and 6, the interior of each section of the shell 4 is provided with horizontal angle-rails 15 permanently secured as by rivets about midway of its height on either side. Fig. 2 shows feed-water heater 6 provided with similar rails 30 16 to cooperate with said rails 15 in supporting the heater within the shell. Boiler 7 is likewise provided with similar rails 17 approximately co-extensive with the firetubes and carrying the entire weight of tube portion 35 of the boiler. To aid support 5 in carrying the weight of the firebox portion of the boiler, and to provide an airtight connection between the boiler and shell section 21, there are provided channel rails 12 (Fig. 40 2) in alignment with rails 17 and extending to the end of the firebox. These rails 12 may be riveted on opposite sides of the boiler. To render air-tight the union between the lower rear edge of shell section 21 and the 45 boiler, a semicircular channel iron 11 is riveted around the lower half of the throat of the boiler. Similarly a channel iron 57 is riveted around the upper half of the rear edge of the boiler. Thus in constructing 50 the steam power plant for a locomotive, said member 25 is inserted (as hereinafter described) in shell-section 22, and then the three shell-sections (20, 21 and 22) are assembled; and then feed-water heater 6 is slid into place through the front end, boiler 7 is slid in from the rear, crown section 9 with its dome cover 23 is put on, and the channel irons 11, 12 and 57 are then bolted to the adjacent edges of the shell. A circular door 18 may be hinged to the front end 55 of shell 4 to close the smoke-box.

60 When it is desired at any time to remove the feed-water heater or the boiler, it is merely necessary to open door 18 in the case 65 of the heater which may then be withdrawn

longitudinally, or to remove section 9 in the case of the boiler, and after unbolting channels 11, 12 and 57 the boiler may be withdrawn rearwardly. If desired cab 10 may be unbolted from section 21 and removed as a unit with section 9, an eye-bolt 13 being located above the center of gravity of this element to facilitate its removal. An alternative arrangement is to form section 9 of uniform height with dome casing 23, in which case this section need not be removed to permit withdrawal of the boiler. In the case of heavy locomotives, it may be desirable to provide additional rails on the shell and heat-exchanging units at suitable points to assist in carrying the load, for example, rails may be provided at the bottom of the shell and cooperating rails on the bottoms of the feed-water heater and boiler.

Referring now to the construction of the heat-exchanging units, as shown in Fig. 3, boiler 7 may be of any usual type, but is here shown as a drum having a front tubesheet 26 and back tubesheet 27 connected by firetubes 28, and is secured in any desired manner to the firebox 8 of any usual construction. In order to limit the forward travel of the boiler when being pushed forward into normal position, there is provided within the adjacent end of one of the two shell-sections 22 and 21, as within the front end of waist-section 21, a stop-ring 29 and a cooperating ring 30 permanently secured near the front end of the boiler. To render the joint between rings 29 and 30 tight, a ring 31 of suitable packing is placed just in front of ring 30 before the boiler is inserted, and will effectually prevent the passage of air when the boiler has been pressed forward to its full extent.

The feed-water heater 6 likewise comprises a drum having front and back tubesheets connected by firetubes. No stop ring is required for the feed-water heater, however, since the union between the front edge of wall 25 and rear edge of the cylindrical shell of feed-water heater 6 need not be gas tight, any combustion gases which pass therebetween serving to heat the exterior surface of the feed-water heater. To give access to the space 14 between the boiler and feed-water heater, there are provided a number of manholes having covers 33, preferably one on either side of the shell 22. To carry hot feed-water from heater 6 to boiler 7, there is provided a delivery pipe 34 leading from the upper portion of the feed-water heater to the bottom of the boiler, this pipe being provided with a suitable check valve (not shown) to prevent reverse flow. Water is forced from the tank into the forward portion of the feed-water heater by any desired type of feed pump or injector (not shown). With the arrangement of the heat-exchanging units shown, it is seen that the

hot gases of combustion pass forward from the firebox through the boiler tubes, thus utilizing the greater part of their heat in the production of steam in the boiler. It is well known, however, that under modern conditions of locomotive firing, the combustion occurring in the firebox and boiler tubes is not complete so that there is still fuel value in the gases, still at a relatively high temperature, when they reach space 14. In order to cause complete combustion of these gases, means are provided for admitting fresh air to the space 14, which air, combining with the hot gases, causes a secondary combustion, and thus constitutes the space 14 a secondary combustion chamber. This heat, together with the specific heat still retained when the gases reach combustion chamber 14 is, to a large extent, utilized in raising the temperature of the feed-water while passing through the firetubes of heater 6.

While any desired means may be employed for admitting fresh air to chamber 14, it has been found most satisfactory to provide a supply pipe 35 having two arms whose front ends are open to the outside air at smokebox front 18, and which arms extend longitudinally through the smokebox and between the heater 6 and shell section 20 rearwardly to secondary combustion chamber 14. The ends of the two arms are joined by a downwardly looping section which is perforated as indicated at 36 (Fig. 3) to permit even distribution of the fresh air throughout the secondary combustion chamber. Suitable means, such as butterfly valves 37, are provided in each arm of air pipe 35 to regulate the flow of air, these valves being controllable from the cab by any desired means (not shown).

While a certain degree of satisfactory operation would result from the employment of only the two heat-exchanging units, namely, the boiler and feed-water heater, already described, a much higher degree of economy will result from the use of a suitable superheater. Superheaters, as formerly employed, have been of very complicated and expensive construction and have required a great deal of maintenance. By the present invention is therefore provided a new superheater 38 which is very similar in construction to a firetube boiler. As seen in Figs. 3 and 4, the superheater comprises a drum 39 positioned in a large flue 40 specially provided in boiler 7. The drum 39 extends from the plane of back tubesheet 27 of the boiler to a point far enough beyond front tubesheet 26 to allow of connection of a dry steam pipe 41 which leads from steam dome 24 through the front tubesheet to the top of the front end of drum 39. In order to conduct the steam entering the superheater over as great a surface as pos-

sible of the superheater firetubes 42, there are provided a number of horizontal baffle plates 43 which extend entirely across the superheater between adjacent rows of tubes 42 and are alternately connected to the front 70 tubesheet and back tubesheet of the superheater. The steam coming from the boiler thus travels in the path indicated by the arrows 44 in Fig. 4, passing the length of the superheater four times and thence 75 through steam pipe 45 to the cylinders. The flow of steam is regulated by any usual throttle valve (not shown).

The superheater may be supported in its flue 40 in any preferred manner, but it is 80 most desirably supported by angle rails 46 (Fig. 6) secured on opposite sides of the inner surface of flue 40, which cooperate with similar rails 47 secured to the drum 39. The superheater is thus made slidably 85 removable from its operative position in the flue. The back sheet of the firebox would, unless specially designed, interfere with the passage of the superheater through the rear end of the locomotive, so that it is desirable 90 to provide for withdrawal of the superheater through the front end. In order to permit such withdrawal through the front end of the locomotive without the necessity of first withdrawing the feed-water heater 95 6, there may be provided a large flue 48 in heater 6, arranged to be in alignment with the superheater and flue 40. Such a large flue 48 would, when open, act as a 100 by-pass to the firetubes of heater 6, to avoid which result there is provided a damper 49 mounted at the front end of flue 48 and quickly detachable therefrom. This damper may be controlled from the cab to regulate 105 the flow of combustion gases.

Owing to the high temperature at the back tube-sheet of the boiler and superheater, and the fact that there is no water in contact with the inside of the back tube-sheet 50 of the superheater, this sheet would quickly burn out unless protected. To prevent such burning out, there is most desirably provided a water header 51 having firetubes 52 arranged to register with the tubes in the superheater. Header 51 is supplied with water from heater 6 by a pipe 53 leading from the lower portion of the heater 6 between the wall of flue 40 and the superheater to the bottom of header 51. A pipe 54 conducts the water which has been considerably heated in the header back to the upper portion of heater 6. This arrangement provides a continuous thermosiphon circulation through header 51 and absolutely protects the back tubesheet 50 of the superheater from burning out while it also aids considerably in raising the temperature of the feed water.

In assembling the locomotive, the sections 20, 21 and 22 of shell 4 are first set up and 130

connected together as by riveting or welding. Combustion chamber wall 25 consisting of internally flanged arcuate plates of cast iron may be next put in place, either a supporting ring 55 being provided, or the front and rear edges of the plates being flanged outwardly to be secured directly to the shell. Stop ring 29 may be permanently positioned on section 21 before assembling the shell. 10 Section 9 of the shell is not bolted on to section 21 until after the boiler is installed, unless the raised crown design of section 9 is used. In case the heat-exchanging units are not completed at this time, the assembled 15 shell may be placed on the main frame 1 of the locomotive.

When the feed-water heater 6 and boiler 7 are ready to be installed, boiler 7 already provided with angle-rails 17 is inserted 20 through the open rear end of the shell, and in the locomotive designed as shown in the drawings crown section 9 is next bolted into place. When shell 9 is provided with the raised crown previously described, it may be 25 bolted on to section 21 before the boiler is installed, since there is room between the crown of the boiler and of shell 9 to permit free passage of dome 24. Feed-water heater 6 may be installed either before or after the 30 installation of boiler 7, it being merely necessary to guide the angle-rails 16 already secured to heater 6 into engagement with their supporting rails 15, carried by shell section 20. The superheater water-header 51 and 35 circulating pipes 53 and 54 are next set in place, the boiler being then ready for superheater 38 which is inserted through flue 48 of the feed-water heater, or which may be placed in the boiler before installation of the same, 40 there being sufficient clearance to allow the passage of the superheater angle-rails 47 through said flue. The steam pipes 41 and 45 are now connected up from the interior of secondary combustion chamber 14, manholes being provided to give access to this 45 chamber as has been described, and the assembly of the heat-exchanging units of the locomotive is complete.

From the foregoing description it is seen 50 that the present invention provides an arrangement of heat-exchanging units which insures complete combustion of the fuel gases and a maximum utilization of the heat therefrom. Moreover, any one of the heat 55 exchanging units may be removed from its operative position without in anyway disturbing the other two heat-exchanging units, and pipes interconnecting the various units are provided with convenient unions to 60 facilitate such independent removability.

By this construction it is no longer necessary to lay up the entire locomotive while some minor repair is made to one of the heat-exchanging units, it being merely necessary 65 to remove the defective unit and replace it

with a spare part kept on hand for the purpose. Thus the percentage of time that a locomotive is on the road is kept a maximum and the time in the shop is made a minimum.

While the construction is primarily designed for use in railroad locomotives, the invention is not limited to this particular application but might be employed with advantage in road engines, steam rollers or possibly even in stationary power plants 75 having a large number of identical steam generating units.

Moreover parts may be used to the exclusion of other parts, e. g. the plant may consist of the boiler and feed-water heater, or the boiler and superheater. In the latter case the header 51 may be used as a feed-water heater, the feed-water being fed from the supply direct to pipe 53, and from pipe 54 to the boiler. This form of the invention may 80 be easily applied to existing locomotives, it being merely necessary to cut out some of the firetubes and replace them with a large flue 40 to accommodate the superheater.

I claim:

1. A steam-generating plant such as a locomotive-engine, comprising an exterior shell, a heat-exchanging unit such as a boiler slideable into and out of one end of said shell and consisting of a drum which has at each end a tube sheet and encloses a plurality of fire-tubes supported by said sheets and has a large and uninterrupted flue through said sheets, a second heat-exchanging drum-unit such as a feed-water heater of similar construction slideable into and out of the other end of said shell and having a large and uninterrupted flue through its tube-sheets, a third heat-exchanging drum-unit such as a superheater of similar construction slideable through the last-named flue and into and out of the first-named flue, said shell enclosing also a secondary combustion-chamber between the adjacent ends of the first two drums aforesaid, a duct admitting air from the front of the locomotive into said space, and detachably-coupled pipes affording communication with the interiors of the respective drums.

2. A steam-generating plant such as a locomotive-engine, comprising an exterior shell, a heat-exchanging unit such as a boiler slideable into and out of one end of said shell and consisting of a drum which has at each end a tubesheet and encloses a plurality of fire-tubes supported by said sheets and has a large and uninterrupted flue through said sheets, a second heat-exchanging drum-unit such as a feed-heater of similar construction slideable into and out of the other end of said shell and having a large and uninterrupted flue through its tubesheets, a third heat-exchanging drum-unit such as a superheater of similar construction slideable through the last-named flue and into

and out of the first-named flue, said shell enclosing also a secondary combustion-chamber between the adjacent ends of the first two drums aforesaid, and a duct admitting air through the front of the locomotive into said space.

3. A steam-generating plant such as a locomotive-engine, comprising an exterior shell, a heat-exchanging unit such as a boiler 10 slidable into and out of one end of said shell and consisting of a drum which has at each end a tubesheet and encloses a plurality of fire-tubes supported by said sheets and has a large and uninterrupted flue through said 15 sheets, a second heat-exchanging drum-unit such as a feed-water heater of similar construction slidable into and out of the other end of said shell and having a large and uninterrupted flue through its tubesheets, and 20 a third heat-exchanging drum-unit such as a superheater of similar construction slidable through the last-named flue and into and out of the first-named flue, said shell

enclosing also a secondary combustion-chamber between the adjacent ends of the 25 first two drums aforesaid.

4. A steam-generating plant such as a locomotive-engine, comprising an exterior shell, a heat-exchanging unit such as a boiler 30 slidable into and out of one end of said shell and consisting of a drum which has at each end a tubesheet and encloses a plurality of fire-tubes supported by said sheets and has a large and uninterrupted flue through said sheets, a second heat-exchanging 35 drum-unit such as a feed-water heater of similar construction slidable into and out of the other end of said shell and having a large and uninterrupted flue through its tube-sheets, and a third heat-exchanging 40 drum-unit such as a superheater of similar construction slidable through the last-named flue and into and out of the first-named flue.

THOMAS F. FITZSIMONS.
